Primary Examiner — Eric L Goodman*Assistant Examiner* — Sanjeev Paul(74) *Attorney, Agent, or Firm* — Sheng-Hsin Hu(57) **CLAIM**

The ornamental design of a contact lens, as shown and described.

DESCRIPTION

FIG. 1 is a front planar view of a contact lens showing my new design;

FIG. 2 is a right side view of the contact lens; and,

FIG. 3 is a left side view of the contact lens.

The broken lines shown in the figure Drawings that are immediately adjacent to the unshaded areas represent the bounds of the claim; the broken lines form no part of the claimed design.
